UNITED STATES PATENT OFFICE.

WILLIAM L. HITCHCOCK, OF PORTSMOUTH, OHIO.

BRICK FOR BAFFLES OR ARCHES OF LOCOMOTIVE FIRE-BOXES.

1,202,887.

Specification of Letters Patent.

Patented Oct. 24, 1916.

Original application filed August 12, 1915, Serial No. 45,210. Divided and this application filed December 27, 1915, Serial No. 68,987. Renewed September 18, 1916. Serial No. 120,888.

To all whom it may concern:

Be it known that I, WILLIAM L. HITCHCOCK, a citizen of the United States, and a resident of Portsmouth, in the county of Scioto and State of Ohio, have invented, certain new and useful Improvements in Bricks for Baffles or Arches of Locomotive Fire-Boxes; and I do hereby declare the following to be a full, clear, and exact description of the invention, such as will enable others skilled in the art to which it appertains to make and use the same.

My invention relates to an improvement in bricks for baffles or arches of locomotive fire boxes and is a division of application Serial Number 45,210 filed by me August 12th, 1915.

The object of this invention is to provide bricks which can be readily and quickly installed in a fire box; which when installed will be locked against accidental displacement, and which are so constructed to deflect the products of combustion against the arch tubes and thoroughly and rapidly mix such products before they pass to the top of the arch.

With these objects in view my invention consists in the details of construction as will be more fully described and pointed out in the claim.

In the accompanying drawings, Figure 1 is a view in plan showing a baffle or arch composed of my improved brick; Fig. 2 is an end view of the same; Fig. 3 is a view in section on the line A—A of Fig. 1; Fig. 4 is a perspective view of one of the bricks, and Figs. 5 and 6 are views in section of same.

In the present instance I have shown four arch tubes 1 communicating at their ends with the boiler, and arranged in two pairs, one pair being at each side of the longitudinal center of the fire box, the space between the inner tubes of the two pairs being greater than the space between the tubes of each pair, and also greater than the space between the outer tubes of each pair and the side sheets 2. This arrangement of tubes is however not essential.

The arch rests upon the arch tubes, and is composed of a central longitudinal row of bricks 3, of the same dimensions, two intermediate rows 4 of the same dimensions and two outer rows 5, all of them being of such

size as to be conveniently handled and passed through the fuel door of the fire box.

The bricks of the central and intermediate rows 3 and 4 are alike, except that the bricks of the center row may be longer than those of the intermediate rows, and each is provided on its lower face with a plurality of ribs 6 forming a series of grooves or channels which extend lengthwise the bricks and transversely of the fire box, and operate to retard and thoroughly commingle the products of combustion in their passage under the arch, and also to direct the said burning and highly heated products transversely and into direct contact with the arch tubes 1 and assist in heating the same. The opposite ends of each of the bricks 3 and 4 are beveled upwardly and inwardly, and each is provided at each end with a mortise 7 preferably rounded as shown, at one side edge with a tenon 8 also preferably rounded, and at its opposite side with a mortise 9 shaped to receive the rounded tenon 8 on the next adjacent brick in its row. The mortises 7 and 9, and tenon 8 of each brick are in the same horizontal plane so as to render them interchangeable, and the ribs 6 on the under side of the central and intermediate rows of bricks are cut away at their extreme ends as at 10, to form curved seats which rest on the arch tubes 1 as clearly shown in Fig. 2, the seats being of less depth than the ribs so as to leave passage ways between said ribs over the arch tubes 1.

The bricks 5 of the two outer rows also have ribs 6 which align with the ribs on the bricks 3 and 4 in the assembled arch, and these ribs are continued up at the outer ends of the bricks as at 11, and are slightly inclined, so that when the outer bricks are assembled in their inclined positions as shown in Fig. 2, the ribs 11 will be approximately parallel with the side sheets 2, and form side channels through which the products of combustion may pass upwardly to the space in the fire box above the arch. The inner ends of the ribs 6 of these bricks 5, are cut away to form recessed seats for the adjacent arch tubes, and their inner ends are each provided with a rounded rib 8a which engages and rests within the mortises 7 in the outer ends of the bricks 4 of the intermediate rows, thus locking the outer rows of bricks to the intermediate rows and preventing

them from having any tendency to ride up on their supporting arch tubes.

The bricks of each row 3—4 and 5, are locked together by mortise 9 and tenion 8 joint, but each of these rows is not connected with others, so that there is but little chance for the bricks of one row becoming fused to those of the adjacent row, while those of each row are purposely connected so as to cause them to fuse, and become united. With an arch thus constructed defective or broken bricks will be retained in place, and may be readily broken apart to remove them when necessary to do so for the purpose of making repairs.

The ribs 11 at the ends of the bricks of the side rows may be readily and quickly trimmed or chipped off in order to properly seat the brick 5 on the tubes 1, and give them the proper inclination with relation to the side sheets and with each other, so that when assembled, the tenon 8 of one will enter the mortise 9 of the next adjacent brick in the same row.

25 The ribs on the underside of the bricks extend throughout the length of the latter, so that the gases and products of combustion in their passage under the arch will be re-

tarded in their movements, and thoroughly commingled before passing into the space 30 above the arch, and some will be deflected laterally against and over the tubes and assist in heating the latter.

By providing the intermediate brick with a mortise 7 at each end the bricks of the two 35 rows will be interchangeable and engage the end tenons 8^a of the bricks of the side rows.

Having fully described my invention what I claim as new and desire to secure by Letters-Patent, is:—

An arch brick for locomotive fire boxes, having a plurality of ribs on its lower face, the said ribs extending lengthwise the brick and throughout the length of the latter, and having concaved seats at their ends to engage 45 two arch tubes, the said seats being of less depth than the ribs so as to leave a passage-way between said ribs over the said tubes.

In testimony whereof, I have signed this specification in the presence of two subscribers 50 and witnesses.

WILLIAM L. HITCHCOCK.
